AUTOMATIC SHAPING ATTACHMENT

Henrik Grondahl and Willem Groen, Chicago, Ill.,
assignors to Onsrud Machine Works, Inc., Chi-
cago, Ill., a corporation of Illinois

Application February 25, 1948, Serial No. 10,738

6 Claims. (CL 144—154)

1

This invention relates to automatic shaping devices and particularly to an attachment for high speed vertical spindle routing machines whereby automatic shaping operations may be performed by the router. Such a device is disclosed in Patent No. 2,107,578 issued February 8, 1938, to Rudolph Onsrud and the present invention is an improvement thereof.

The main objects of this invention are to provide an improved attachment for performing shaping operations on a routing machine; to provide such a device having dual feed tables operable alternately under positive drive and work clamp control for automatic, substantially continuous production; to provide such a device having dual feed tables and independent work clamps which operate automatically prior to engagement of the work with the cutter; and to provide such a device having dual feed tables that are automatically shifted alternately into and out of operative position relative to the cutter and wherein actuation of the automatic work clamps for the respective feed tables is separately controlled by operation of the feed table shifting means.

Other objects of this invention are to provide a shaping attachment for routers having improved fully automatic control of feed table drive and work clamp operation; to provide such a device having dual feed tables and wherein control of the respective feed table drive and work clamp operation is governed by the position of the feed tables relative to the cutter; and to provide such a device wherein feed table position, feed table drive and work clamp operation are governed accurately by a single power actuator which in turn is remotely controlled by the operator.

A specific embodiment of this invention is shown in the accompanying drawings in which:

Figure 1 is a front view, in perspective, showing the general organization of the invention as embodied in a vertical spindle router.

Fig. 2 is a plan view of the improved automatic shaping attachment with the main gear box cover in section to show the actuating mechanism.

Fig. 3 is an enlarged plan view of the automatic work clamp control means, the gear box cover on which the same is mounted being partly broken away.

Fig. 4 is a view of the same as taken on line 4—4 of Fig. 3, and

Fig. 5 is a plan view in section of one of the work clamp control valves shown in Figs. 3 and 4.

In the form shown in the drawings, the improved shaping attachment is embodied in a

single spindle, vertical head, high speed router and referring to Fig. 1, it will be seen that this router comprises a spindle head 1, mounted at the forward end of a horizontal arm 2, extending from an upright or frame portion 3 of a routing machine which also includes a horizontal work table 4 mounted for vertical adjustment in the usual manner on the main router frame. The spindle head includes a downwardly projecting spindle shaft 5 on the lower end of which is a chuck which is adapted to hold the shaft of a router bit or cutter 7; and the spindle shaft 5 is driven by a suitable power means, not shown, housed within the body of the routing machine frame.

The improved attachment is designed to be mounted on top of the work table 4 and comprises a stationary base member 8, arranged to support a shiftable carrier or sub-base 9, which in turn carries the automatic shaping mechanism, work clamps, driving means and controls. The base member 8 is secured on the work table 4 by means of suitable dowels, not shown, which fit into suitable apertures provided in the table 4.

As shown, the carrying member or sub base 9 is pivotally connected at its rear end to the main base member 8 as shown at 10 in Fig. 2 and is arranged to be oscillated laterally across the top of the main base between a pair of adjustable limit stops each of which comprises an adjustable screw 11 threaded through a stop block 12 welded onto the upper surface of the main base 8. Each screw 11 is provided with a hand knob 13 and a lock nut 14 is threaded on the screw to bear against the block 12 and lock the screw in whatever position it might be set.

The sub-base 3 carries a pair of rotatable feed tables 15 arranged one on each side of the fore and aft horizontal center line of the sub-base 9 so that upon shifting of the sub-base laterally, one way or the other, work carried by the feed tables 15 may be brought into engagement with the router 7. The feed tables 15 are also spaced apart laterally so that when the work on one table is in engagement with the router 7, the other feed table will be at an adequate distance from the cutter to permit the work being changed safely by the operator.

In the form shown, the work holding clamps 16 are supported on fixed vertical posts 17, mounted on the sub-base 8 and disposed laterally and to the rear of the respective feed table axes. Each of the clamps 16 is vertically adjustable on its respective post 17 and comprises a pneumatically actuated arm extending outwardly over

the respective feed table 15 and having a clamping head 18 vertically aligned with the feed table axis. The motors or air cylinders 19 for actuating the clamps 16 are disposed at the rear end of the respective clamps and air under pressure is supplied to the motors 19 by means of hose connections 20 and 20.1 as will be later described. Pneumatic clamps of this type are well known in this art and their construction and operation will be readily understood by those skilled in the art.

The oscillating carrier member or sub-base 9 is actuated, to move the feed tables laterally toward and away from the rotating cutter 7, by means of an air operated piston or power device 21 which is mounted on the main base 8 and which operates through a connection to the sub-base 9 contained within a gear box 22. Control means through which operation of the work clamps 16 is regulated is mounted on top of the gear box 22 and the hose connections 20 and 20.1 for supplying air to the respective clamp motors 19, lead to this control means which is indicated generally in Fig. 1 by the numeral 23.

Power for driving the feed tables 15 is supplied by an electric motor 24 which has a pulley and belt connection with the driving means contained in the gear box 22, as will be later more fully described.

Also, as shown in Fig. 1, a fixed position pattern follower or guide 25, which comprises a roller pivotally mounted on an arm 26, is provided to control the relation of the cutter and the work. The roller arm 26 extends inwardly from a bracket 27 and holds the roller 25 so that it is axially aligned with the cutter 7, the bracket 27 being a relatively heavy rigid member mounted fast at the forward edge of the main base 8 and stationary relative to the shiftable sub-base 9.

Referring to Fig. 2, it will be seen that the power cylinder or device 21, which causes lateral shifting of the sub-base 9 to bring the feed tables 15 alternately into operative position, also serves to simultaneously shift the feed table drive mechanism from the inoperative table to the operative feed table.

As before-mentioned, power for the feed table drive is obtained from an electric motor 24 which is mounted on the sub-base 9 and which, through a motor pulley 28, a belt 29 and a shaft pulley 30, drives the main power shaft 31. The power shaft 31 is suitably supported in bearings 32 and 33 and is constantly in rotation so long as the electric motor 24 is being driven. Transmission of power from the shaft 31 to the respective feed tables 15 is obtained through a friction clutch mechanism 34, which is driven by the shaft 31 and which is arranged to selectively drive gears 35 and 36 carried by the shaft 31. The gears 35 and 36 are arranged to be freely rotatable on the shaft 31, except when they are engaged by the clutch.

The friction clutch 34, illustrated herein, is a double-acting multi-disc clutch, of well-known construction, having a central collar in which a shifting fork may be engaged and which is operable axially of the drive shaft 31 to cause driving engagement with the gears 35 and 36.

As shown in Fig. 2, the driving gear 35 is meshed with a driven gear 37 which is fast on a shaft 38 disposed parallel with the main drive shaft 31 and extending into a gear casing 39 on which the right-hand feed table 15 is mounted. Inside the gear casing 39 the shaft 38 carries a worm 40, indicated in dotted outline, which is

meshed with a worm gear 41 mounted on the axis of the feed table 15 and connected in driving relation thereto by means of a vertical drive shaft 42. Thus when the clutch 34 is in position to drive the driving gear 35, the right-hand feed table is positively driven from the main shaft 31 by way of the gear 37, shaft 38, worm 40 and worm gear 41.

The drive for the left-hand feed table 15 is substantially identical with the feed table drive just described, except that the power from the main shaft 31 is taken from the driving gear 36 directly connected to a driven gear 43 which in turn drives a suitable worm and gear arrangement contained in the left-hand gear housing 44 on which the left-hand table is mounted.

As shown in Fig. 2, the sub-base or carrier 9 is laterally shiftable across the upper surface of the main base 8 and relative to the cutter 7. The sub-base or carrier 9 is connected to the main base 8 by the pivot 10 and is supported on a pair of rollers 45 disposed at opposite sides of the sub-base and carried in suitable roller support brackets 46 which are bolted onto the sub-base and which extend through suitable apertures, not shown, in the sub-base so that the rollers may bear on the top surface of the main base 8.

The power cylinder 21 is pivotally mounted, at its outward end, on the main base 8 by means of a vertical pivot connection 47 and is connected to the shiftable sub-base 9 by means of a piston rod 48 projecting from the inner end of the power cylinder 21 and attached to one arm of a lost motion means or limited movement bell crank 49 by means of a pivot connection 50, the bell crank 49 being pivotally connected to the sub-base 9 by a suitable pivot pin or stub-shaft 51 which is mounted fast on the sub-base and projects upwardly therefrom inside the gear housing 22.

The other end of the piston rod 48 is directly connected to a double-acting piston 52 in the power cylinder 21, which piston is actuated by compressed air supplied through the air tubes 53 and 54. Thus upon actuation of the piston 52 in either direction, the piston rod 48 causes the sub-base 9 to shift in the same direction through the connection with the bell crank 49 and its pivot connection 51 on the sub-base.

A second arm 55 on the bell crank 49 carries a fork arrangement 56 having sliding connection with the clutch mechanism 34, whereby a simultaneous shift in the transmission of power, to the appropriate gear train for the feed tables 15, is had whenever a shifting movement is imparted through the bell crank to the sub-base 9. Thus, when the sub-base is shifted from one side to the other by the power cylinder 21, the shifting force first acts to turn the bell crank and operate the clutch mechanism so that driving engagement of the feed table drive gears with the main drive shaft 31 is likewise shifted to operate the feed table moving toward the cutter.

It will now be seen that upon actuation of the piston 52 in the power cylinder 21, the first effect will be to shift the feed table driving mechanism through the lost motion means or bell crank 49 and that thereafter a shifting of the sub-base 9 will occur. Therefore, to relieve the clutch mechanism 34 of the turning moment or load imparted to the bell crank 49 as the power force is being transmitted through the pivot post 51 to the sub-base 9, the bell crank is provided with a third arm 57 arranged to provide limit stops for the bell crank movement.

In the form shown, the bell crank arm 57 is

constructed with a vertical opening 58 into which a stop post 59, fixed to the sub-base 9 projects and adjustable limit stop members comprising a pair of stop screws 60 are threaded through opposite end walls of the opening 58 so as to be engageable with the fixed post 59 to limit the turning movement of the bell crank 49.

The purpose of the bell crank connection between the sub-base 9 and the power cylinder 21 is to effect automatic control of the feed table operation as the sub-base is shifted from side to side by the power cylinder 21 and only such turning movement of the bell crank as will effect actuation of the clutch mechanism 34 is necessary. Therefore, the stop screws 60 are adjustable so that the precisely necessary movement of the bell crank may be set according to the clutch requirements.

Upon shifting of the sub-base 9 to bring the feed tables 15 alternately into operative relation with the cutter 7, it is also desired that the pneumatic clamps 16 be simultaneously actuated in properly timed relation so that the work will be securely clamped to the feed table that is being moved into operative position well in advance of the time when actual engagement of the work with the cutters occurs. This is accomplished by governing the clamp operation from control means actuated by the bell crank 49.

This control means, indicated generally by the numeral 23 in Fig. 1, is shown in detail in Figs. 3 to 5 inclusive and comprises a pair of balanced air valves 61 and 62 connected in tandem by a common link 63 for simultaneous operation. These valves, however, are arranged in opposed relation so that one opens as the other closes and each is connected to control a respective pneumatic clamp by means of the air hoses 20 and 20.1. As shown in Fig. 3, the air supply to the valves 61 and 62 is common to both and comes from a pressure source, not shown, through a connection 64 to a manifold 65 connected to the inlet side of each valve. The outlets 66 and 67 of the respective valves are connected to the flexible hoses 20 and 20.1 respectively.

The two air valves are of the same construction and they are merely positioned with their inlets and outlets facing in like directions and with their operating stems extending toward each other. Thus, referring to Fig. 5, wherein details of the valve 61 are shown, it will be seen that the valve body is a T-shaped member having opposed inlet and outlet openings and having a centrally disposed balanced valve member 68 operating along the axis of the central leg in a sleeve 69 which has suitable inlet and outlet ports 70 and 71 spaced apart axially. The valve 68 has a stem 72 which is attached to a connector member 73 arranged for axial movement within a connector sleeve 74 and the parts are secured in the valve assembly by a bonnet 75 threaded onto the valve body.

The valve 68 is thus arranged to open and close communication between the ports 70 and 71 by a reciprocating movement with the inner end of the valve disposed between the ports when communication is closed. This leaves the ports 71 in communication with a bleed port 76 whenever the valve 68 is in its outer or closed position, whereby pressure in the supply side to the clamp motor may be relieved. When the valve is in its open position its inner end moves beyond the ports 71 and closes off the bleed outlet while air is flowing between the ports 70 and 71. As shown in Fig. 5, the outer end of the connector 73 is bifurcated

to receive one side of the link 63 and is fastened to the link by a pin 77.

As shown in Figs. 3 and 4, the valves controlling flow of air pressure to the clamp motors 19 are operated simultaneously as the clutch mechanism 34 is operated by the bell crank arm 55 to shift the drive from one feed table 15 to the other and such operation of the valves is also obtained from the same bell crank arm. This is accomplished by means of an operating pin 78 which extends upwardly from the bell-crank arm 55, through the drive housing 22, and into an opening 79 in the link 63 which connects the two valve connector members 73. Thus, as the bell-crank is actuated angularly to shift the drive from one feed table to the other the operating pin 78 is shifted likewise and the clamp control valves are simultaneously and immediately operated to actuate one clamp motor and cause release of the other clamp motor.

The location of the operating pin 78 on the bell crank arm 55 is determined by the operating stroke of the clamp motor control valves, which is preferably less than the operating stroke or movement of the clutch mechanism 34, so that full operation of the valves will occur before full engagement of the clutch 34. The location of the operating pin thus determines the location of the valve assembly on the gear box cover 22 since the vertical plane containing the valve axes should also contain the axis of the pin when the crank arm is in the mid-position of its stroke. The opening 79 in the valve connecting link 63 is slightly elongated, transverse its direction of movement, to accommodate the arcuate path of the pin as the crank arm 55 swings from side to side.

In the arrangement shown, the operating pin opening 80 in the drive housing cover 22 is closed by a sliding plate 81 carried by the pin 78 in order to prevent leakage of lubricant and the plate 81 is held tightly against the cover by means of a spring 82 bearing between the plate and the link 63.

In operation the improved shaping attachment is mounted horizontally on the table 4 of a vertical spindle router and the main base 8 is secured to the table 4, by suitable means, not shown, in such a position that the pattern follower or guide roller 25 is directly aligned with the router spindle axis. The power cylinder 21 is then connected to a suitable reservoir of compressed air through a power cylinder control valve, not shown, which directs the air through the air hoses 53 and 54 alternately to actuate the piston 52. Air from the same reservoir is also supplied to the clamp control valve manifold 65 and power for the feed table drive is furnished by the motor 24 which drives the main shaft 31 continuously while the attachment is in use. The cutter 7 is driven from its own power source, not shown, in the spindle head.

Normally the sub-base 9 will be swung to one side of the main base 8, to the left as shown in Fig. 2, where it will be engaged by the respective limit stop screw 11 and the feed table 15 of the opposite side will be in operative position. The operator then mounts the desired pattern on the inoperative feed table, farthest from the cutter, and places the blank to be shaped on top of the pattern. Then by operation of the power cylinder control valve the piston 52 is actuated to swing sub-base 9 to the opposite side causing the loaded feed table to be moved toward the cutter 7.

Immediately that the piston 52 is actuated to swing the sub-base, the bell crank 49 is caused to

pivot until its right hand limit stop screw 60 engages the fixed post 59. This movement of the bell crank causes immediate shifting of the feed table drive, from the right hand table to the left hand table, through operation of the clutch mechanism 34, and simultaneously actuates the clamp control valves to actuate the left hand clamp and begin release of the right hand clamp.

The clamping operation of each clamp is arranged to be slightly in advance of full engagement of the clutch mechanism with the respective driving gear 35—36, through an excess in the valve stroke so that the work is securely clamped in place on the feed table before it begins to revolve and, because the clutch is operated as the sub-base first begins to swing, the feed table is in full rotation before the cutter engages the work.

Because the shifting of the sub-base 9 is by air pressure there is a resiliency to its movement which permits the cutter to work its way gradually into the blank to be shaped until the follower roller 25 engages the pattern after which the roller 25, by acting on the pattern periphery, determines the depth of the cut by causing shifting of the sub-base to move the operating feed table toward or away from the cutter according to the pattern profile. The resilient force of the air pressure in the power cylinder 21 keeps urging the feed table into the cutter and thus permits the roller 25 to accurately follow the pattern.

While the left hand feed table rotates to feed the work to the cutter, the operator loads the right hand table which is swung clear. Then, as soon as the shaping cut is completed on the left hand feed table, the operator operates the power cylinder control valve and the sub-base is caused to swing to the left to bring the right hand feed table work and pattern into engagement with the cutter and follower. The shifting of the feed table drive from left table to right table is immediate, as is the action of the right table clamp to hold the work. Also, the rotation of the left table stops as the table moves outwardly away from the cutter. The work clamp of the inoperative table, however, is slower in its releasing action due to the fact that its release is by a bleed-off of the actuating air through the respective control valve 61 or 62. This permits the finished work to be swung clear and a complete stopping of table rotation before full release of the clamp occurs. The speed of clamp release can be regulated by controlling the rate of bleed-off through the valve port 71 and past the valve 63 to the valve outlet 76.

While the right feed table is in operative position, and during the shaping of the blank thereon, the operator removes the finished piece from the left table and places another blank. Then, when the right table shaping operation is finished, the left table is brought back to operative position by operation of the power cylinder control valve and the process is repeated.

In some operations it is desirable for the operator to physically retard the swinging movement of the sub-base 9 under the influence of the power cylinder 21 and for this purpose handles 83 are provided at each side of the sub-base where the operator can hold onto the sub-base as it moves from side to side. Ordinarily the operating line air pressure is from 90 to 100 lbs. per square inch.

The main advantages of this invention reside in the facility for converting a router to an automatic shaper for faster and more accurate shaping operations on small parts made of material

75 with cutting characteristics similar to wood; and in the arrangement of the device whereby high speed shaping operations can be performed with practically continuous production on alternately operative feed tables which, together with the work, are under automatic and accurate control at all times that the device is in operation.

Further advantages are to be found in the automatic control arrangement for the feed table drive and the work holding clamps whereby the operator is free to concentrate solely on the operation of loading and unloading feed tables. And still further advantages are to be found in the control arrangement whereby the shift of feed table drive and the operation of the work clamps occurs at the beginning of the movement of the shiftable feed table carrier to bring a blank into engagement with the cutter; and in the arrangement of the work clamp control whereby the clamp is actuated to secure the blank prior to full engagement of the feed table drive.

Although but one embodiment of this invention is herein shown and described, it will be understood that numerous details of the construction shown may be altered or omitted without departing from the spirit of the invention as defined by the following claims.

We claim:

1. A device of the class described comprising a laterally shiftable carrier having a pair of spaced rotatable feed tables and means for driving said feed tables, a double acting pneumatic cylinder and piston connected to said carrier and adapted to shift said carrier from side to side relative to a medially positioned rotary cutter and thereby move said feed tables alternately into operative position with the cutter, means to direct compressed air to each side of said cylinder selectively, an automatic work clamp disposed above each feed table and supported from said carrier, pneumatic motor means for operating each work clamp, a pneumatic pressure supply connection for each of said motor means, control means for directing pressure through said supply connections alternately, and means connecting said control means with said piston for operation of said control means by reciprocal movement of said piston and according to the direction of movement of said carrier, the connection of said piston with said carrier including lost motion means for limited movement of the piston relative to the carrier whereby said control means is operated prior to the shifting movement of said carrier.

2. A device of the class described comprising a laterally shiftable carrier having a pair of spaced rotatable feed tables, means for shifting said carrier alternately from side to side relative to a medially positioned rotating cutter, means for operating said carrier shifting means, a power actuated work clamp disposed above each feed table, drive means on said carrier for driving said feed tables and including shiftable clutch means for connecting said drive means with said tables alternately, a clutch-shifting lever pivoted on said carrier and connected with said carrier shifting means for angular operation thereby according to the direction of movement of said carrier, clamping control means on said carrier having a power connection with each of said clamps and operable between two positions for energizing said clamps alternately, and means on said clutch-shifting lever and connected with said control means for operating said control means in predetermined relation with the operation of said clutch.

3. A device of the class described comprising a laterally shiftable carrier having a pair of spaced rotatable feed tables and means for driving said feed tables, power means having a driving connection with said carrier for shifting said carrier alternately from side to side relative to a medially positioned rotating cutter, means for operating said power means intermittently, an automatic work clamp disposed above each feed table, an individual operating means for each of said work clamps, control means having power supply connection with the respective clamp operating means and operable between two positions to actuate the same alternately, said control means being mounted on said carrier adjacent said driving connection, and said driving connection including a shiftable member movable in response to force applied thereto by said power means and engaged with said control means for operating said control means according to the direction of movement of said carrier.

4. A device of the class described comprising a laterally shiftable carrier having a pair of spaced rotatable feed tables and means for driving said feed tables, power means connected to said carrier for shifting said carrier alternately from side to side relative to a medially positioned rotating cutter, means for operating said power means, an automatic work clamp disposed above each feed table, an individual operating means for each of said work clamps, control means having individual power supply connection with each of said clamp operating means and operable between two positions to actuate the same alternately, said control means being mounted on said carrier and movable therewith, and shiftable means having a lost motion connection with said carrier and connected to and actuated by said power means and having connection with said control means for operating said control means according to the direction of movement of the carrier and immediately prior to movement of the carrier.

5. A device of the class described comprising a laterally shiftable carrier having a pair of spaced rotatable feed tables and means for driving said feed tables, power means connected to said carrier for shifting said carrier alternately from side to side relative to a medially positioned rotating cutter, means for operating said power means, an individual work clamp disposed above each feed table, an individual operating means for each of said work clamps, oppositely operating dual control means each having a power supply connection with a respective clamp operating means and operable to energize and de-energize

the same, a shiftable member connected to said power means and actuated thereby and having operating connection with both of said control means for actuating said control means simultaneously in respectively opposite directions to operate one clamp and release the other according to the direction of movement of said carrier, and means for retarding the releasing action of each of said clamps.

10 5 15 20 25 30 35 40 45

6. A device of the class described comprising a base, a laterally shiftable carrier on said base having a pair of spaced feed tables and drive means operatively connected with said feed tables to rotate the same, said drive means including a double acting clutch for connecting said feed tables with said drive means selectively, a rigid pivot mounted fast on said carrier, a bell crank rotatively mounted on said pivot and having one arm operatively connected to said clutch, reciprocal operating means on said base connected to a second arm of said bell crank for turning said bell crank to operate said clutch and then shift said carrier from one side to the other to move the driven feed table into operative position with a medially positioned rotating cutter, stop means rigidly mounted on said carrier for limiting the rotation of said bell crank in either direction by engagement with an arm thereof, a work clamp mounted on said carrier and disposed above each feed table, operating means for each work clamp, and work clamp control means having a shiftable power switching member operatively connected with said bell crank and having power connection with each of said clamp operating means, said switch member being movable between two positions for directing power from said control means to the respective clamp operating means alternately in accordance with the direction of angular movement of said bell crank and prior to movement of said carrier.
